UNITED STATES PATENT OFFICE.

ALBERT L. PLATT, OF BOWLING GREEN, MO., ASSIGNOR, BY DIRECT AND MESNE ASSIGNMENTS, TO W. B. McPIKE, CHAMP CLARK, ALEXANDER McDANNOLD, E. T. SMITH, AND J. D. HOSTETTER, ALL OF SAME PLACE.

NUTMEG-GRATER.

SPECIFICATION forming part of Letters Patent No. 334,279, dated January 12, 1886.

Application filed September 29, 1885. Serial No. 178,556. (No model.)

To all whom it may concern:

Be it known that I, ALBERT L. PLATT, of 5
Bowling Green, in the county of Pike and
State of Missouri, have invented a new and
useful Improvement in Nutmeg-Graters, of
which the following is a description.

Figure 1 is a perspective view. Fig. 2 is a
central vertical section, and Fig. 3 is a detail
side view of the cylinder.
10 My invention is in the nature of an im-
proved nutmeg-grater designed for great sim-
plicity, durability, and effectiveness; and it
consists in a revolving barrel made of a spiral
coil of steel wire having notched outer edges,
15 in combination with a frame composed of a
block having a hole through it, and a coun-
ter bore or hole at right angles, which forms
the case in which the spiral cylinder revolves.

In the drawings, A represents the case,
20 which may be of any material, but which, as
shown, is made of a wooden block having a
hole, *d*, bored through the same. Another
hole, *e*, is bored laterally through the block at
right angles to the first hole and intersecting
25 it. This latter hole forms a case, in which re-
volves a grating-cylinder, B, composed of a
spiral coil of steel wire. One end of this spiral
is bent to form a crank, *c*, on one side of the
block, by which the cylinder is turned, and
30 within the spiral cylinder is soldered, paral-
lel with its axis, a short rod or section of wire,
b, whose end is bent around outside of the
block and prevents the spiral cylinder from
slipping out of its case.

35 The grating-surface of the cylinder is formed

of notches or jogs cut transversely upon the
outer periphery of the coils of the wire. The
cylinder thus constructed revolves in the case
upon the bearings afforded by its own periph-
ery.

40 In using the grater, the nutmeg is placed in
the hole *d*, and is pressed upon the revolving
grater by the thumb of the hand that holds
the block, while the other hand turns the
crank to revolve the grating-cylinder. The
45 nicks or notches on the cylinder grind off the
nutmeg, the particles of which drop through
the spiral coil and pass out of the hole below.

Having thus described my invention, what
I claim as new is—

50 1. The combination, with a case, of a revolv-
ing grating-cylinder composed of a spiral coil
having a nicked periphery and bearings for
sustaining the cylinder, substantially as de-
scribed.

55 2. The combination, with a block having a
hole bored through it and another at right an-
gles, of a spiral coil having a nicked periph-
ery and means for holding it in place and turn-
ing it, as described.

60 3. The combination, with a case, of a spiral
coil having a nicked periphery and a crank at
one end and an outturned section of wire, *b*,
at the other to hold it in place, substantially
as described.

ALBERT L. PLATT.
